UNITED STATES PATENT OFFICE.

SAMUEL NEWMAN, OF NEW YORK, N. Y.

DENTAL ABSORBENT-ROLL HOLDER.

Application filed October 26, 1921. Serial No. 510,562.

To all whom it may concern:

Be it known that I, SAMUEL NEWMAN, a citizen of the United States, residing at New York city, in the county of New York and State of New York, have invented certain new and useful Improvements in Dental Absorbent-Roll Holders, of which the following is a specification.

My present invention relates to improvements in dental absorbent roll holders such as are used to hold rolls of cotton in position to absorb saliva in oral operation.

One of the objects of my invention is to provide such a holder which can be utilized at the same time to hold the mouth open at any height. Another object of my invention is to arrange such a device so that the width may be adjusted to suit the mouth of the patient. Another object of my invention is to provide such an arrangement by which cotton rolls may be held at either side of the gum on both the upper and lower jaws simultaneously.

With these and other objects in view, my invention consists in the arrangements and constructions illustrated in the drawings, and more specifically pointed out in the appended claims.

In the drawings, Figure 1 shows, on a scale larger than actual size, one form of my invention; Fig. 2 is a section and Fig. 3 a side elevation of the arrangement shown in Fig. 1, but very much enlarged; Fig. 4 is a section and Fig. 5 a side elevation of another form of my invention.

Corresponding reference characters refer to corresponding parts in the several views.

Referring first to the form of my invention embodied in Figs. 1, 2 and 3, the absorbent rolls R, which usually are made up of absorbent cotton but may be of any other absorbent material, are pushed on the pins 10, which in the form illustrated, are two in number, each arranged to be located at either side of the patient's gum. To each of the pins 10 is connected a member 11, and to each of the members 11 are connected a pair of posts 12, the upper ends of which pass into tubes 13, connected to a saddle 14 arranged to contact with the opposite jaw of the patient, as directly against a tooth as shown in Fig. 2. Within the tubes 13 and pressing against the upper ends of the post 12 are spiral springs 15 which normally push the post 12 downward until the

projection on the end thereof contacts with the bottom of the tube.

With the construction just described, cotton rolls are impaled on the pins 10 and the device inserted in the mouth of the patient with the rolls in the positions indicated. The patient then opens his mouth to the desired extent and as he does so, the springs 15 will hold the saddle 14 against the upper jaw and this, in turn, will hold the cotton rolls R in place. If desired, the jaws of the patient may be held open by clamping the post 12 in the tube 13 at any desired position, this clamping being provided for, in the form illustrated, by splitting the two outer tubes 13, as at 16, and providing a compression nut 17 threaded on a crew 18, so that the split portion of the tube may be compressed on the outer end of the post 12. If desired, a similar arrangement may be provided on the other two posts also.

In the form illustrated in Figs. 4 and 5, a pair of pins 20 are provided for the lower jaw and another pair of pins 21 for the upper jaw, absorbent rolls being mounted on these pins as before described. Each of the pins 20 is mounted on a member 22 and each of the pins 21 on a member 23. To the member 22 is connected a single post 24, the upper end of which slides in a tube 25 provided with a spring 26 similar to that described in the arrangement shown in Fig. 1. Similarly the member 23 is provided with a post 27 sliding in a tube 28, provided with a spiral spring 29. The tube 25 may be split, as at 30, and provided with a compression nut 31, operating in the manner described in connection with the arrangement shown in Fig. 1.

It will be obvious that, in the arrangement shown, the pressure of the springs 26, 29 will hold the upper and lower absorbent rolls in position, and that similarly the jaws of the patient may be held open any desired amount by the use of the clamping nut 31.

In some cases, it is desirable to be able to adjust the width of the holding device, and I have shown such an arrangement in connection with the form illustrated in Figs. 4 and 5, though it will be understood that a similar arrangement may be applied to the modification shown in Fig. 1.

To accomplish this end, I provide a tube 32 which, in the form illustrated, is con-

2
nected at right-angles to the tube 28, and a post 32 connected to the tube 25, having its end inserted in the tube 32. A spring 34 tends to move the tube 25 away from the 5 tube 28. A clamping nut 35 is provided to lock the post 33 in any desired position in relation to the tube 34. With the arrangement shown, the device may be adjusted laterally so as to space the absorbent rolls 10 crosswise of the gum at the correct distance, in accordance with the width of the patient's mouth.

It will be understood that the arrangements which I have shown are merely 15 illustrative, and that the details of such constructions may be varied within wide limits.

I claim:-

1. In a dental absorbent roll holder, a pair of roll holders arranged to hold the 20 roll on either side of the gum, an abutment frame arranged to extend across the gum and to contact with the opposite jaw, and a yielding extensible connection between said abutment frame and each of said roll 25 holders arranged to exert a vertical straight-line pressure between each roll holder and the abutment frame.

2. In a dental absorbent roll holder, a pair of roll holders arranged to hold the 30 roll on either side of the gum, an abutment frame arranged to extend across the gum and to contact with the opposite jaw, and a yielding extensible connection between said abutment frame and each of said roll 35 holders arranged to exert a vertical, straight-line pressure between each roll holder and the abutment frame, said connection comprising a telescoping rod and tube and a spiral spring to exert pressure to extend 40 the connection.

3. In a dental absorbent roll holder, a pair of roll holders arranged to hold the roll on either side of the gum, an abutment frame arranged to extend across the gum 45 and to contact with the opposite jaw, a yielding extensible connection between said abutment frame and each of said roll holders arranged to exert a vertical, straight-line pressure between each roll holder and the abutment frame, and means on each connection to hold the roll holder connected thereto in predetermined relation to the abutment frame.

4. In a dental absorbent roll holder, a 55 roll holder arranged to hold a roll on the side of the gum, a member adapted to be moved toward the opposite jaw, a yielding connection, comprising a spiral spring, between the holder and the member, said spring being arranged, when unopposed, to

move the member away from the holder, and means to hold the connection to restrain the action of the spring.

5. In a dental absorbent roll holder, a roll holder arranged to hold a roll on the side 65 of the gum, a member adapted to be moved toward the opposite jaw, a yielding connection between the holder and the member, and means to hold the holder and the member at a predetermined distance apart.

6. In a dental absorbent roll holder, a pair of roll holders arranged to hold a roll on either side of the gum, a member adapted 70 to be moved toward the opposite jaw, connections between the roll holders and the member, an adjustable connection between the roll holders, whereby the distance between the holders across the gum may be varied, and means to lock the adjustable connection in adjusted position.

7. In a dental absorbent roll holder, a pair of roll holders arranged to hold a roll on either side of the gum, a member adapted 75 to be moved toward the opposite jaw, connections between the roll holders and the member, an adjustable connection between the roll holders, comprising a spiral spring, arranged to move the holders apart crosswise of the gum, and means to clamp the adjustable connection in adjusted position 80 to restrain the action of the spring.

8. In a dental absorbent roll holder, a pair of bottom roll holders arranged to hold a roll on either side of the gum on the lower jaw, a pair of top roll holders arranged to hold a roll on either side of the gum on the upper jaw, yielding connections between the top and the bottom holders to move them apart and press the rolls against their respective jaws, and adjustable connections 95 between the holders of each pair of roll holders, whereby the distance between the holders crosswise of the gum may be adjusted.

9. In a dental absorbent roll holder, a pair of bottom roll holders arranged to hold a roll on either side of the gum on the lower jaw, a pair of top roll holders arranged to hold a roll on either side of the gum on the upper jaw, yielding connections between the top and the bottom holders to move them apart and press the rolls against their respective jaws, means to hold said roll holders in a predetermined relative position, and adjustable connections between the holders 100 of each pair of roll holders, whereby the distance between the holders crosswise of the gum may be adjusted.

SAMUEL NEWMAN.
